Howard T. Chapman

UNITED STATES PATENT OFFICE.

JOHN T. CHENEY, OF SWARTHMORE, PENNSYLVANIA, ASSIGNOR TO THE CONGOLEUM COMPANY, OF PHILADELPHIA, PENNSYLVANIA, A CORPORATION OF PENNSYLVANIA.

FLOOR-COVERING.

1,292,705.

Specification of Letters Patent. Patented Jan. 28, 1919.

Application filed October 7, 1918. Serial No. 257,164.

To all whom it may concern:

Be it known that I, JOHN T. CHENEY, a citizen of the United States, and a resident of Swarthmore, county of Delaware, State of Pennsylvania, have invented certain Improvements in Floor-Coverings, of which the following is a specification.

The invention relates to certain improvements in floor coverings of the oil cloth type. One object of the invention is to make a floor covering having a felt base and a linseed oil and filler composition wearing surface.

A further object of the invention is to provide means for mechanically holding the wearing surface firmly to the felt base.

A still further object of the invention is to relieve the felt base from pressure so as to prevent indenting of the wearing surface to any considerable extent.

These objects I attain in the following manner, reference being had to the accompanying drawings in which:

Figure 1 is an enlarged sectional view illustrating my improved floor covering before being compressed;

Fig. 2 is a view similar to Fig. 1, with the material compressed;

Fig. 3 is a perspective view partly in section showing the perforated base and the wearing surface;

Fig. 4 is a sectional view showing a modification in which there is a binder between the base and the wearing surface;

Fig. 5 is a perspective view illustrating a modification in which the base is punctured to provide a roughened perforated surface; and

Figs. 6 and 7 are views showing the base having an undercut perforation and the material forced into the perforations.

Referring to Figs. 1, 2 and 3 of the drawings, 1 is a felt base, which is impregnated with a semi-solid bituminous material. This felt base is made of dry felt, preferably from cotton rags, cotton waste, or other suitable material and the felt is saturated with a substance which will thoroughly impregnate it, making it pliable and proof against moisture.

The substance I prefer to use consists of petroleum flux oil and a residual pitch derived from asphaltic or semi-asphaltic base oils, but other hydrocarbons may be used, if desired. The material is heated and placed

in a saturating kettle so as to allow it to pass into the felt. During the saturating process, the material will thoroughly impregnate the felt. The felt is then allowed to cool and is perforated, as at 2. The perforations may be of any shape and size desired and may be straight, as shown in Figs. 1 and 2, or may be undercut as shown in Figs. 6 and 7, or the perforations may be made by puncturing the back 1^a, as at 2^a, Fig. 5, so as to form a roughened surface to which the wearing surface will readily adhere.

3 is the wearing surface of a linseed oil composition, in the present instance consisting of linseed oil and a filler of floured wood pulp. This surface is applied to the base 1 in the same manner that linoleum is applied to a burlap base. Pressure is then applied so as to force the surface composition through the perforations in the felt 1, at the same time reducing the thickness of the felt base, as shown in Fig. 2. Fig. 1 shows the felt base before being reduced by pressure and also shows the wearing surface before being compressed.

I have found it difficult to secure the wearing surface to the felt base by simply pressing the wearing surface onto the base, as it is liable to separate, due to the peculiar character of the saturating composition for the felt, but by perforating the base I find that the wearing surface will enter the perforations and will mechanically hold the wearing surface to the base. Furthermore, by making the perforations of considerable size, such as shown in Figs. 1, 2 and 3 of the drawings, the surface will extend entirely through the base and will support the wearing surface, preventing to a great extent the indentation of the floor covering when furniture is resting upon it, which is due to the fact that the felt base alone will yield under pressure, whereas the material of the wearing surface will sustain its load and also has a tendency to return to its normal condition after pressure is applied, so that the projecting of the surface material into the perforations not only unites the two surfaces, but also acts as a support for the wearing surface.

In some instances, as illustrated in Fig. 4, an asphalt binder may be used between the wearing surface and the felt base, and this binder will cause the two materials to adhere one to the other, particularly as the binder

may extend into the perforations between the projections and the walls of the perforations, as clearly shown in Fig. 4.

I claim:—

1. A floor covering consisting of a perforated felt base and a composition wearing surface having projections extending into the perforations of the base.
2. The combination of a perforated felt base, said perforations being undercut, and a linseed oil composition wearing surface hav-

ing projections extending into the undercut perforations of the base.

3. The combination in a floor covering, of a felt base saturated with a semi-solid bituminous material and having perforations, and a cork composition wearing surface applied to the felt base by pressure so as to cause the material of the wearing surface to be projected into the perforations.

In witness whereof I affix my signature.
JOHN T. CHENEY.
